UNITED STATES PATENT OFFICE

158,858

PAIR OF SCISSOR GRIP PLIERS

Louis W. Hodge, Sr., Phenix City, Ala.

Application June 6, 1947, Serial No. 139,503

Term of patent 3½ years

(Cl. D54—13)

To all whom it may concern:

Be it known that I, Louis W. Hodge, Sr., a citizen of the United States, residing at Phenix City, in the county of Russell and State of Alabama, have invented a new, original, and ornamental Design for a Pair of Scissor Grip Pliers, of which the following is a specification, reference being had to the accompanying drawings, forming part thereof.

In the drawings:

Figure 1 is a side elevational view of a pair of scissor grip pliers showing my new design;

Figure 2 is an edge elevational view; and

Figure 3 is a side elevational view showing the pliers in opened position.

I claim:

The ornamental design for a pair of scissor grip pliers, as shown.

LOUIS W. HODGE, Sr.
